FUR AND FABRIC WHIPPING MACHINE

Charles M. McCarthy, Minneapolis, Minn.

Application December 8, 1937, Serial No. 178,721

5 Claims. (Cl. 15—92)

This invention relates to a device for treating articles made of fur and certain fabrics. Such articles particularly articles of dress made of fur and certain fabrics are now commonly cleaned in either cleaning machines or by hand processes. It is usually necessary after such cleaning to beat the fur or treat it so that it is brought back to a uniform upstanding position so as to give the best appearance. It is also the common practice to place fur coats and other similar articles in cold storage during the summer months. It frequently and usually happens that after such storage the fur on the articles has been pressed down flat in whole or in part so that the fur is not in uniform condition. In such cases it is also necessary to treat or whip the fur to bring it back to the best condition. In most fur shops at present this treating or whipping operation is done by hand and it is usually done by the use of paddles manipulated by the operators. It is desirable to have a power driven tool or device which can readily be moved about and which will act on the fur to bring it back to its proper upstanding position so as to have its best appearance.

It is an object of this invention therefore, to provide a simple, compact and conveniently mounted device and one which can be easily and conveniently moved about the same comprising a shaft with a plurality of flexible straps arranged for treating the fur or fabric.

It is another object of the invention to provide such a device comprising a motor having an armature shaft and a second shaft extending laterally adjacent one end of said motor and at right angles to said armature shaft together with means for driving said second shaft from said armature shaft and means for conveniently suspending and manipulating said device.

It is still further an object of the invention to provide a fur treating device comprising a motor and a shaft extending laterally therefrom together with a novel form of handle for conveniently and comfortably manipulating the device and a novel form of suspending means for suspending the device in balanced position.

These and other objects and advantages of the invention will be fully set forth in the following description made in connection with the accompanying drawing in which like reference characters refer to similar parts throughout the several views and in which—

Fig. 1 is a view in side elevation of the device showing the same in suspended condition, some

portions being broken away and others shown in vertical section;

Fig. 2 is a view in end elevation as seen from the right of Fig. 1; a portion of the supporting means being omitted; and

Fig. 3 is a partial plan view of the device.

Referring to the drawing a device is shown comprising a shaft 10. Shaft 10 is shown as having a rounded free end and the same is provided with a plurality of slots 10a extending diametrically therethrough, the same being shown as rectangular in cross section. Said slots 10a are equally spaced longitudinally of said shaft and while the number may be varied, in the embodiment of the invention illustrated said slots 10a are shown as six in number. Three of said slots extend at right angles to the other three and are arranged alternately therewith. Straps 11 extend through certain of the slots 10a and extend at substantially equal distances at opposite sides of the shaft 10. Other straps 12 extend through the other slots 10a and at equal distances at either side of the shaft 10. Straps 12 thus will be arranged alternately with the straps 11. Straps 11 and 12 will be held in place in shaft 10 by the screws 13 threaded into said shaft and engaging said straps at their inner ends. Screws 12 will preferably be provided with slots in their ends for convenient removal and tightening. Shaft 10 is slightly enlarged at its secured end and is journaled in bearings 14a and 14b formed adjacent one end of a motor 14. Shaft 10 has secured thereto within the casing 14c from which said bearings extend a worm wheel gear (not shown) and said worm wheel gear is in mesh with a worm gear secured to the armature shaft 14d of motor 14. Bearing 14b is illustrated as having a circular flange at one end secured in place by the screws 15. While various types of motors could be used the one that has been used in practice and which is shown in the drawing is provided adjacent one end with a ventilating fan drawing air through the motor casing 14e and discharging the same through one or more slots at the lower end of the casing. The motor casing 14e is illustrated as of cylindrical shape and the same has a pad 14f formed at the side thereof opposite that from which shaft 10 extends. Said pad has a plane outer surface and has secured thereto by the countersunk screws 16 one end of a handle member 17. Handle member 17 as shown is formed of a flat strip of metal having rounded edges and said handle extends upward along the pad 14f and is then reversely bent in the arc of a circle and has a free end portion ex-

tending parallel to the axis of motor 14, the lower end of said portion being curved outwardly slightly. A pad 18 is secured to the inner side of the handle 17 by any suitable means such as by cementing and pad 18 extends slightly at either side of the handle 17. While said pad may be made of any suitable soft material, in practice it has been made of felt and the same extends from the inner side of the bent portion of handle 17 to its terminal end. A pad 19 is provided which pad extends from the inner end of the pad 18 to the lower inner end of handle 17. Pad 19 is also secured in any suitable manner as by cement and said pad extends some distance at either side 15 of the handle 17 and is curved to extend substantially around the motor casing 14e. While different materials might be used for pad 19, in practice it is made of soft leather. A switch 20 for starting and stopping the motor 14 is provided 20 and positioned at one side of the motor closely adjacent the top thereof and substantially in horizontal alignment with the top of the handle 17. Switch 20 has a small lever 20a having a ball shaped end which is moved from side to side to 25 shut off or turn on the motor respectively. Switch 20 is so positioned that it can be conveniently operated by the thumb or finger of the operator when his hand is in operative relation to the device. A bail member 21 is provided also 30 formed of a comparatively thin strip of metal, the same having a semi-cylindrical top portion with straight sides extending along the sides of the motor 14. Said bail is secured by the screws 22 adjacent its ends which are threaded into casing 35 14e. Said bail also fits over projections or pins 23 extending from the motor casing. It will be noted that member 21 extends upwardly from substantially the center of the motor at an angle and toward the side of the motor from which 40 shaft 10 projects. The upper end member 21 is thus at one side of the axis of the motor and armature shaft. Member 21 has an eyelet 24 secured in its upper end and shown as riveted therein. Eyelet 24 forms the supporting means 45 for the device and the same is shown engaged by a snap hook 25 secured to the lower end of a cord or cable 26, the upper end of which is provided with a loop 26a connected by a link 27 to a loop 28a formed on the lower end of a flexible strip 50 28 extending into a casing 29. Casing 29 is shown as having a flat bottom and a semi-cylindrical upper portion. Member 28 is in the form of a flat strap and has connected to one end a spiral tensile spring of flat material disposed in casing 55 29 and one end of which will be secured to a shaft 30 disposed in casing 29 and having portions 30a journaled in the sides thereof. The said spring resiliently supports the device and strap 28 can move more or less out of casing 29 as the device 60 is supported and moves about.

In operation the device is mounted as shown in Fig. 1. The operator preferably places his hand within handle 17 with the palm of the hand against the pad 19. This hand can thus extend 65 around motor casing 14e very comfortable and the back of the hand is pressed against pad 18. In this manner the device can be very conveniently and effectively manipulated to bring the straps 11 and 12 into contact with the garment surface whether the same is vertical, horizontal or in any other position. The motor can be conveniently controlled by the operator by moving switch lever 20a with his thumb or finger. The straps 11 and 12 are rotated at the desired speed 70 and are brought so that they strike against the

garment and whip up the fur or fabric to the desired condition. By the use of the device the fur is brought to the best possible condition and a very uniform effect can be produced.

The present device is an improvement upon 5 that shown in applicant's co-pending application S. N. 155,650.

By having the shaft 10 project at right angles to the armature shaft and driven from the latter a more satisfactory arrangement as to speed can 10 be had. Also by having the strap shaft 10 at right angles to the armature shaft the gyroscopic effect produced by rotation of the parts is greatly reduced. The device can be much more easily moved into different positions at different 15 angles than when all of the parts rotate about one axis. By having the member 21 extending to one side of the axis of the armature shaft the device is suspended in balanced condition or so that shaft 10 is normally horizontal. At the same 20 time the suspending cable 26 is not spaced far from the axis of the armature shaft or the axis of the motor. The axis of the motor thus does not have to move very far out of alignment with the suspending cable 26 in the various movements 25 of the device. These advantages over the device shown in the previous application are very pronounced in practice. It is also very convenient to have the switch located where it can be readily operated by the operator at any time 30 while he is using the device.

The device has been amply demonstrated in actual practice and found to be very successful and efficient. The same has been received with enthusiasm where it has been used in fur establish- 35

It will, of course, be understood that various changes may be made in the form, details, arrangement and proportions of the parts, without departing from the scope of applicant's invention, which generally stated, consists in a device 40 capable of carrying out the objects above set forth, in the parts and combinations of parts disclosed and defined in the appended claims.

What is claimed is:

1. In a device for treating fur or fur fabrics having a substantially horizontal beater shaft and a motor for driving the same, said motor having a cylindrical casing with a substantially vertical axis, the combination of a pad extending concentric with the surface of said casing adjacent thereto and a handle extending upwardly from the top central portion of said pad and reversely curved to extend substantially parallel thereto and having a free lower end. 55

2. In a device for treating fur or fur fabrics constructed and arranged to be suspended by a flexible member and counter-balanced, the combination of a motor having its armature shaft extending substantially vertically, a beater shaft 60 extending at right angles to said armature shaft, gearing connecting said shafts to drive said beater shaft at a different speed from said armature shaft, a handle for manipulating said device secured to the side of said motor at the side 65 opposite said beater shaft and a suspension member secured to the sides of said motor and extending above said armature shaft, the same having means for attachment to said flexible member disposed in a vertical plane passing through the 70 center of gravity of said device whereby said beater shaft will be disposed in substantially horizontal position.

3. In a device for treating fur or fur fabrics comprising a beater shaft arranged to normally 75

- be disposed horizontally and beaters secured to said shaft, the combination of a motor forming part of said device and adapted to be moved and manipulated with said device, said motor having its armature shaft disposed vertically and having a casing secured thereto into which said beater shaft extends, a reduction gearing in said casing between said armature shaft and beater shaft for driving the latter at much less speed than said motor, a handle secured at one cylindrical side of said motor opposite said beater shaft and a suspension means extending vertically from and secured to said motor.
5. In a device for treating fur or fur fabrics comprising a beater shaft arranged to normally be disposed horizontally and beaters secured to said shaft, the combination of a motor adapted to be moved and manipulated with said device, said motor having its armature shaft disposed vertically and having a casing secured thereto into which said beater shaft extends, a bail bracket extending over said motor and armature shaft and having side portions secured to the sides of said motor, a flexible supporting means swivelly connected to the top of said bracket, said bracket extending at an angle to the vertical and toward the side of said motor on which said beater shaft is disposed so that the center of said supporting means extends substantially through the center of gravity of said device so that said device is normally balanced with said beater shaft in horizontal position.
10. In a device for treating fur or fur fabrics comprising a beater shaft arranged to normally be disposed horizontally and beaters secured to said shaft, the combination of a motor adapted to be manipulated with said device, said motor having its armature shaft disposed vertically and having a casing secured thereto into which said beater shaft extends, a bail bracket extending over said motor and armature shaft and having side portions secured to the sides of said motor, a flexible supporting means swivelly connected to the top of said bracket, said bracket extending at an angle to the vertical and toward the side of said motor on which said beater shaft is disposed so that the center of said supporting means extends substantially through the center of gravity of said device so that said device is normally balanced with said beater shaft in horizontal position.
15. In a device for treating fur or fur fabrics comprising a beater shaft arranged to normally be disposed horizontally and beaters secured to said shaft, the combination of a motor adapted to be moved and manipulated with said device, said motor having its armature shaft disposed vertically and having a casing secured thereto into which said beater shaft extends, a handle secured to the cylindrical side of said motor opposite said beater shaft for manipulating said device and a bail projecting upward from said motor over said armature shaft having its ends secured to the sides of said motor and extending at an angle toward the side of said motor ad-
20. In a device for treating fur or fur fabrics comprising a beater shaft arranged to normally be disposed horizontally and beaters secured to said shaft, the combination of a motor adapted to be manipulated with said device, said motor having its armature shaft disposed vertically and having a casing secured thereto into which said beater shaft extends, a bail bracket extending over said motor and armature shaft and having side portions secured to the sides of said motor, a flexible supporting means swivelly connected to the top of said bracket, said bracket extending at an angle to the vertical and toward the side of said motor on which said beater shaft is disposed so that the center of said supporting means extends substantially through the center of gravity of said device so that said device is normally balanced with said beater shaft in horizontal position.
25. In a device for treating fur or fur fabrics comprising a beater shaft arranged to normally be disposed horizontally and beaters secured to said shaft, the combination of a motor adapted to be manipulated with said device, said motor having its armature shaft disposed vertically and having a casing secured thereto into which said beater shaft extends, a bail bracket extending over said motor and armature shaft and having side portions secured to the sides of said motor, a flexible supporting means swivelly connected to the top of said bracket, said bracket extending at an angle to the vertical and toward the side of said motor on which said beater shaft is disposed so that the center of said supporting means extends substantially through the center of gravity of said device so that said device is normally balanced with said beater shaft in horizontal position.

CHARLES M. McCARTHY.
